TYPOGRAPHICAL SLUG CASTING MACHINE

William Fairall Gorse, Altrincham, and Richard Henry Scott, Enfield, England, assignors to Linotype and Machinery Limited, London, England, a company of England

Application March 17, 1934, Serial No. 716,114
In Great Britain April 6, 1933

16 Claims. (Cl. 199—50)

This invention relates to typographical slug casting machines such as those known commercially under the registered trade-mark "Linotype", wherein circulating matrices are composed in line and the composed line presented to a slotted mould for the casting of the type bar or slug, the line, during the casting operation, being positioned between a pair of line clamping jaws which are ordinarily set to receive a line of predetermined length.

In order to provide for the production of slugs with blank spaces at the ends, for quadding or centring, without the necessity of filling out the composed line with blanks or quads, it has been proposed to provide means for automatically moving one or other, or both, of the jaws inwardly for the clamping of composed lines of less than full length. In these arrangements, however, the composed line itself acts as a stop for the inward movement of the jaw or jaws, so that the length of the blank space at the respective end of the slug is determined by the length of the composed line, subject in some cases, to a limited outward movement of the jaws to allow for a predetermined maximum expansion of the line during justification when expansible space-bands are used.

The object of the present invention is to provide means independent of the composed line, adjustable to determine the extent of the inward movement of the movable jaw or jaws, whereby the length of the blank space, or spaces produced on the slugs, is determined by the adjustment of the jaw or jaws, instead of by the length of the line, so that a definite indent may be produced on the cast slug, the end of the slug at which such indent is produced being determined by the particular jaw in connection with which the quadding adjustment is provided.

The invention may be carried out conveniently by arranging an adjustable stop in the path of the respective jaw during its inward movement, or in the path of a member of the jaw adjusting mechanism, which can be set to determine the desired extent of said inward movement or thrown out of action when not required.

The invention is hereinafter more particularly described with reference to the accompanying drawing showing one constructional form thereof. In the said drawing:—

Figure 1 is an elevation of the pertinent parts of the vise frame of a machine with the invention applied thereto;

Figure 2 is a plan view, partly in section, of the vice devices according to the invention, the vice

frame of the machine being indicated in dot-and-dash lines;

Figure 3 is an elevation as seen from the left-hand side of Figure 1, of the means for adjusting the stop, some of the parts being broken away 5 and some omitted.

According to the constructional form of apparatus illustrated in the drawing, the inward movement of the jaws 1, 2, for quadding or centring, is effected by a vertically movable operating rod 3. This rod is operatively connected with or disconnected from the respective jaws through levers 4, 5, pivoted to the vice frame 6, and having on their shorter arms pins extending beneath a collar 26 angularly adjustable at the 15 upper end of the rod 3. The collar 26 is formed with segmental projections which are brought into and out of engaging relationship with the pins by angular adjustment of the collar so that either or both of the jaws 1, 2, may be moved inwardly for quadding or centring by the operation of the rod.

As this arrangement, and the devices for operating the rod, do not per se constitute part of the present invention, it is deemed unnecessary to include herein any further detailed description or illustration thereof.

In applying the invention to the constructional form of quadding and centring apparatus above referred to, the adjustable stop is preferably 30 adapted to engage with a stop member 7 secured to the jaw-operating rod 3, and in the preferred arrangement now to be described, the adjustable stop and its adjusting devices are provided in the form of a self-contained unit supported in a 35 bracket 8 which can be attached to the vice frame 6 of the machine.

Referring first to Figure 1, the adjustable stop 9 is carried by a bar 10 which is slidable in a guideway on the bracket 8 constituted by side 40 members 11 and keeper plates 12. The adjusting devices for the stop 9 comprise a lever 13, one end of which turns about a fixed pivot 14 on the bracket 8. The free end of the lever 13 is pivoted to a link 15 which is in turn pivoted to a 45 stud 16 (see particularly Figure 3), which is adjustable along a slot 17 in the bracket 8. The lever 13 is provided with a pin 18 located between the ends of the lever projecting rearwardly therefrom into engagement with a forked bracket 19 secured to the bar 10.

As shown best in Figure 3, the stud 16 extends through the slot 17 in the bracket 8, and at its outer end is fitted with an adjustable knob 20 which is axially movable on the stud 16 but is 55

angularly fast thereto. A spring 21, acting between the knob 20 and a collar 22 on the stud 16, normally urges the knob 20 towards the bracket 8, and for the purpose of retaining the knob in any of its adjusted positions a rack 23 is formed on or secured to the bracket 8, this rack 23 extending parallel with the slot 17 so as to engage teeth formed on the inner face of the knob 20, whatever the position of the latter along the said slot. A scale 24 arranged parallel with the slot 17 may be secured to the bracket 8 for co-operation with a pointer 25 on the knob 20 in determining the necessary adjustment for an indent of any desired length.

15 The constructional form of the invention above described operates as follows:—When, for example, an indent of 6 ems, is required on a slug of normal length, the stud 16 is adjusted along the slot 17 until the pointer 25 registers with the 6 em mark on the scale 24, and locked in that position by the action of the spring 21 on the release of the knob 20 at the completion of the adjustment. Through the consequent movement of the lever 13 the bar 19 is adjusted to set 20 the stop 9 at the desired distance below the stop 7 on the jaw-operating rod 3. The just-described position of adjustment is indicated in Figure 1, wherein also both jaws 1, 2, are represented as connected to the jaw-operating rod 3; thus, when 25 the rod 3 is moved downwardly to effect the inward movement of the jaws, such downward movement will be arrested by the contact of the stop 7 with the stop 9, and the jaws 1, 2, consequently held in the position indicated in dotted 30 lines in Figure 1 to produce an indent of 6 ems at both ends of the slug to be cast. A corresponding indent may, of course, be produced at either end of the slug as desired by connecting only the respective jaw to the rod 3. When it is 35 desired to operate the quadding and centring devices normally, i. e., without producing a predetermined indent, the stop 9 may be rendered inoperative by setting its adjusting devices in the lowermost position indicated by dot-and-dash lines in Figure 1. In cases where the quadding and centring devices are arranged to permit, in 40 normal operation, an outward yielding of the jaws during the justification of lines containing spacebands, the indenting stop may be used in conjunction with means for limiting or preventing such outward yielding, which means, however, constitute no part of the present invention.

It is to be understood that the constructional form of the invention and of the quadding and centring devices above described and illustrated in the accompanying drawing has been chosen merely as convenient examples, and that the invention contemplates variations in the form of the stop and its adjusting devices to suit any particular form of jaw-operating mechanism to which the invention is to be applied.

Having described our invention, we declare that what we claim and desire to secure by Letters Patent is:—

65 1. In a typographical slug casting machine, the combination with a pair of line clamping jaws and a periodically operated device connectible to at least one of said jaws and operable to effect inward movement of the connected jaw towards a composed line located between the jaws, of an abutment on said device, a slide adjustable relatively to said device, a stop on said slide located in the path of the said abutment, a lever turning on a fixed pivot and a projection on

the lever intermediate its ends engaging a forked member secured to the slide.

2. In a typographical slug casting machine, the combination with a pair of line clamping jaws and a periodically operated device connectible to at least one of said jaws and operable to effect inward movement of the connected jaw towards a composed line located between the jaws, of an abutment on said device, a slide adjustable relatively to said device, a stop on said slide located in the path of the said abutment, a lever turning on a fixed pivot, a projection on the lever intermediate its ends engaging a forked member secured to the slide, and a locking device adapted to secure the lever and slide in different positions of adjustment.

3. In a typographical slug casting machine, the combination with a pair of line clamping jaws and a periodically operated device connectible to at least one of said jaws and operable to effect inward movement of the connected jaw towards a composed line located between the jaws, of a stop adjustable to determine the extent of the operative movement of said periodically operated device, a setting device for the said stop and a support for said stop and setting device attachable to and detachable from the machine frame.

4. In a typographical slug casting machine, the combination with a pair of line clamping jaws and means adapted to move at least one of said jaws inwardly from its line receiving position relatively to the other jaw to cooperate with a line of matrices of less than full length, of means independent of the matrix line for limiting the inward movement of the jaw to arrest it in a definite position.

5. In a typographical slug casting machine, the combination with a pair of line clamping jaws and means adapted to move at least one of said jaws inwardly from its line receiving position relatively to the other jaw to cooperate with a line of matrices of less than full length, of means for limiting the inward movement of the jaw to arrest it in a definite position, said limiting means being adjustable to arrest the jaw in different positions for cooperation with lines of different lengths.

6. In a typographical slug casting machine, the combination with a pair of line clamping jaws and means adapted to move either of said jaws inwardly from its line receiving position relatively to the other jaw to cooperate with a line of matrices of less than full length, of means independent of the matrix line for limiting the inward movement of either jaw to arrest it in a definite position.

7. In a typographical slug casting machine, the combination with a pair of line clamping jaws and means adapted to move both of said jaws inwardly from their line receiving position relatively to each other to cooperate with a line of matrices of less than full length, of means independent of the matrix line for limiting the inward movement of the jaws to arrest them in a definite position.

8. In a typographical slug casting machine, the combination with a pair of line clamping jaws, one movable inward relatively to the other for quadding, and automatic means for effecting such inward or quadding movement of the jaw, of adjustable means independent of the composed line to arrest the jaw in its inward movement and thereby determine its quadding position.

9. In a typographical slug casting machine, the combination with a left hand line clamping jaw

- and a right hand line clamping jaw, the left hand jaw being movable inward relatively to the right hand jaw for quadding, and automatic means for effecting such inward or quadding movement 5 of the left hand jaw, of adjustable means independent of the composed line to arrest the left hand jaw in its inward movement and thereby determine its quadding position.
10. In a typographical slug casting machine, 10 the combination with a pair of line clamping jaws, each movable inward relatively to the other for quadding or centering, automatic operating means for said jaws, and means adapted to render said operating means effective on either jaw independently or upon both jaws simultaneously, 15 of means independent of the composed line to limit the inward movement of either or both jaws and thereby determine its or their quadding or centering position.
20. 11. In a typographical slug casting machine, the combination with a left hand line clamping jaw and a right hand line clamping jaw, and automatic means adapted to move the left hand jaw inwardly from its line receiving position to 25 cooperate with a line of matrices of less than full length, of means for limiting the inward movement of the left hand jaw to arrest it in a definite position short of line contacting position.
12. In a slug casting machine, the combination 30 of a pair of relatively movable line clamping jaws, mechanism for moving one of the jaws inwardly from its line receiving position relative to the other jaw into contact with the line or for arresting the jaw in its inward movement so

as to locate it in a definite position independently of the line, and means for conditioning said mechanism according to one alternative or the other.

13. A combination as in claim 12, wherein the 5 jaw moving mechanism includes adjustable means for determining the extent of inward movement of the jaw when moved to a definite position independently of the line.

14. In a slug casting machine, the combination 10 of a pair of relatively movable line clamping jaws, mechanism for moving one of the jaws inwardly from its line receiving position relative to the other jaw into contact with the line or to a definite position independently of the line, and means 15 for conditioning said mechanism according to one alternative or the other.

15. In a slug casting machine, the combination 20 of a pair of relatively movable line clamping jaws, mechanism for moving one of the jaws inwardly from its line receiving position relative to the other jaw for quadding, and adjustable means to allow the jaw to be located in quadding position by contact with the line or to locate the jaw in a quadding position independently of the 25 line, as required.

16. A combination according to claim 14, wherein the adjustable means includes a stop settable manually in any desired position when the jaw is at rest, and operative to locate the 30 jaw in a corresponding position during the quadding operation.
